UNITED STATES PATENT OFFICE.

BERNHARD BETHKE, OF MILWAUKEE, WISCONSIN, ASSIGNOR TO LUTHER GRINDER MFG. CO., OF MILWAUKEE, WISCONSIN, A CORPORATION OF WISCONSIN.

CLAMPING SUPPORT FOR GRINDING MACHINES.

1,404,337.

Specification of Letters Patent. Patented Jan. 24, 1922.

Application filed March 10, 1920. Serial No. 364,715.

To all whom it may concern:

Be it known that I, BERNHARD BETHKE, a citizen of the United States, residing at Milwaukee, county of Milwaukee, and State 5 of Wisconsin, have invented new and useful Improvements in Clamping Supports for Grinding Machines, of which the following is a specification.

My invention relates to improvements in 10 clamping supports for grinding machines and other small manually driven tools adapted to be secured to a bench or table.

The object of my invention is to provide 15 means whereby a grinding wheel or other rotative tool may be supported to revolve about an axis oblique to the front margin of the bench or table, and driven by a crank which revolves in a plane oblique to such margin, the machine being adequately secured and rigidly held to such bench or 20 table, notwithstanding its oblique position.

It is a further object of my invention to 25 provide means whereby grinding wheel mechanisms and similar devices may be not only supported in the oblique position above mentioned, but may also, with equal facility, be clamped to the table or bench in the ordinary manner, with the tool supporting arbor or shaft at right angles to the front 30 margin of the support.

In the drawings:—

Figure 1 is a plan view of a grinding wheel clamping support embodying my invention, showing the same as it appears in 35 use with the grinding wheel arbor obliquely disposed.

Figure 2 is an elevation of the mechanism, including the clamping support.

Figure 3 is a sectional view, drawn to a 40 plane on line 3—3 of Figure 2.

Like parts are identified by the same reference characters throughout the several views.

The grinding wheel casing 1 may be of 45 any ordinary type. The casing illustrated is provided with a driving shaft 2 having an exterior crank 3. The driven shaft or arbor 4 supports the grinding wheel 5, and is driven from the shaft 2 by a gear wheel and 50 pinion, indicated by dotted lines at 6 and 7. All of these parts, however, may be of any ordinary construction.

But it will be observed that the casing 1 is supported by a base plate 10, preferably 55 formed integrally with the bottom and front

wall of the casing, but this base plate 10 is of peculiar contour. It is of a generally triangular form, with the right hand side margin 10^a extending forwardly to an apex 10^b, located at the right of a vertical plane through 60 the axis of the crank shaft 2. The left hand margin has one portion 10^c extending from the left hand side of the casing toward the vertical plane of the crank shaft, along a line which is substantially parallel to the 65 margin 12 of the table or bench when the device is secured to such table with the arbor 4, at an angle of approximately 45° to the table margin. Between the portion 10^c of the base plate margin and the apex 10^b, the 70 base plate margin is outwardly curved, as indicated at 10^d, and this outwardly extending portion of the plate is provided with a depending arm 13 having a horizontally extending extremity 14, which projects un- 75 derneath the table or bench, and through which a clamping set screw 15 passes, the upper end of this set screw being provided with a swiveled clamping head 17 adapted to engage the under surface of the table or 80 bench, whereby the set screw may be utilized to draw the clamping plate 10 forcibly downwardly on the upper surface.

It will be observed that the form of the clamping plate 10 is such that the right 85 hand marginal portion 10^a extends inwardly upon the surface of the table along a line substantially at right angles to the margin 12 of the table, although the base plate margin is preferably slightly curved for the 90 purpose of attractive design. Therefore, space is provided at 16 for the crank handle, the same being allowed to turn without striking either the base plate or the table.

On the other side, (i. e., the left hand side), 95 the contour of the base plate 10 is such as to interfere to a minimum extent with the manipulation of tools and devices of various kinds which are being subjected to a grinding operation. The fact that the grinding 100 wheel revolves in an oblique plane is of great importance for the reason that many tools, such as chisels and long knives, or other tools with long handle, are frequently of such character that in order to get the 105 best results the handles must be swung downwardly across the plane of the table, and unless the grinding wheel is located in an oblique plane sufficient clearance cannot be obtained.

Where ordinary clamping plates are employed, the desired adjustment of the grinding wheel cannot be secured,—at least without greatly weakening the clamping engagement with the table. This is true for the reason that when the casing is rotated to the oblique position, the clamping arm corresponding with the arm 13 will strike the table on the right hand side, whereas the upper clamping plate will be entirely out of contact with the table on the left hand side, and the clamping pressure being exerted considerably to the right of the center of gravity of the machine, considerable vibration results in operation, and the fastening becomes very insecure.

By my improvement, the clamping arm 13 is brought to the left, and the clamping pressure is exerted centrally, i. e., substantially directly below the center of gravity of the machine. The wide bearing area of the clamping plate upon the table at the points most distant from its front margin 12 and from the point at which the arm 13 is located, is also a factor in securing rigidity and stability for the support.

The larger area of the clamping plate is provided at the right hand for the reason that the majority of users operate the grinding machine with the right hand, and hold the tool with the left hand. Therefore, the described contour of the clamping plate provides clearance for the tool at the side where clearance is normally desired.

I claim:—

A clamping support for grinding machines and similar tools, comprising a base plate of substantially triangular contour, a gear casing carried by said base plate adjacent one of the triangular sides, said gear casing having a driving shaft bearing arranged at an acute angle to another of said triangular sides, and a clamping arm extending downwardly from said last mentioned side and beneath said base plate.

In testimony whereof I affix my signature in the presence of two witnesses.

BERNHARD BETHKE.
